Primary Examiner — Paula Allen Greene*(74) Attorney, Agent, or Firm* — Sterne, Kessler, Goldstein & Fox P.L.L.C.(57) **CLAIM**

The ornamental design for earphones, as shown and described.

DESCRIPTION

FIG. 1 is a top front perspective view of earphones showing the claimed design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the figures show portions of the earphones that are for illustrative purposes only; the broken lines form no part of the claimed design.

It is certified that error appears in the above-identified patent and that said Letters Patent is hereby corrected as shown below:

On the Title Page

In the Description item (57), replace the following paragraph:

“The broken lines in the figures show portions of the earphones that are for illustrative purposes only;
the broken lines form no part of the claimed design.”

With:

--The broken lines in the figures show portions of the earphones that form no part of the claimed
design.--

Signed and Sealed this
Twentieth Day of October, 2020

Andrei Iancu
Director of the United States Patent and Trademark Office
